EXTRUSION FOR A SAILBOAT MAST

Lars Rune Bergstrom, Sodernas Fyr, 13030 Värmdö,
Sweden, and Georg Sven Olof Ridder, 12 Fregattvagen,
18137 Lidingö, Sweden

Filed Aug. 23, 1973, Ser. No. 390,745

Term of patent 14 years

Int. Cl. D12—99

U.S. Cl. D12—70

FIG. 1

FIG. 2

FIG. 3

FIG. 1 is a perspective view of an extrusion for a sailboat mast embodying our design as seen from above the front right-hand side thereof and with a lower portion broken away to indicate indeterminate length;

FIG. 2 is a perspective view of the extrusion as seen from above the rear right-hand side thereof;

FIG. 3 is a top plan view of the extrusion.

The bottom plan view of the extrusion is identical to the top plan view shown in FIG. 3. Additionally, the transverse cross section of the extrusion at any point along its axis is identical to that depicted in FIG. 3, it being understood that the cross section of the extrusion is continuous and uniform throughout the length of the extrusion.

We claim:

The ornamental design for an extrusion for a sailboat mast, as shown and described.
